UNITED STATES PATENT OFFICE.

THEODORE SMITH, OF PHILADELPHIA, PENNSYLVANIA.

WINDOW-SCREEN.

SPECIFICATION forming part of Letters Patent No. 411,088, dated November 18, 1890.

Application filed May 8, 1890. Serial No. 351,033. (No model.)

To all whom it may concern:

Be it known that I, THEODORE SMITH, a citizen of the United States, residing at Philadelphia, in the county of Philadelphia and 5 State of Pennsylvania, have invented certain new and useful Improvements in Window-Screens and Apparatus for Use Therewith, of which the following is so full, clear, and exact a description as will enable others skilled 10 in the art to which my invention appertains to make and use the same, reference being had to the accompanying drawings, in which—

Figure 1 is an inside view in elevation of a 15 window-case, showing my improved devices in position when in use. Fig. 2 is a vertical longitudinal sectional view of the same. Fig. 20 3 is a detail view of the bifurcated arrow-head catches and stops for engaging therewith. Fig. 4 is a perspective of the same, showing thumb-pieces for disengaging the catches.

The object of my invention is to provide a 25 screen and receptacle for the same, by the use of which the screen may be used when desired without any trouble on the part of the operator.

Another object of my invention is to provide a screen which may be readily and easily 30 secured and attached from the window-sash by one not particularly skilled in mechanics in the shortest possible time and with the least expense of physical and mechanical force.

Another object of my invention is to provide a screen which shall be neat in appearance and which shall snugly fit the window-frame and present the most artistic appearance possible for a device of this kind, so far 40 as regards the means of attachment of the screen.

It is well understood that the screens ordinarily in use are too cumbersome and the plan of their operation such that much trouble is 45 experienced in adjusting them to fit the spaces left by the open window.

In the accompanying drawings, A designates an ordinary window-sash provided with slot b, provided with suitable escutcheon c.

B designates the screen and screen-frame, which is provided with suitable projections or staples f, adapted to fit into the openings

in the bottom of the sash, and they are designed to be firmly held in place by suitable catches f² f², provided with posts H' adapted 55 to slide in slots J J in the window-sash.

A receptacle or casing is designated by the letter C, and this casing or receptacle or well is let into the bottom of the window-sill and is of such dimensions as to facilitate the ready 60 and easy insertion of the screen therein and also its ready removal therefrom when desired for use.

From the foregoing it will appear that the screen may be readily attached or detached. 65 It may be stored away in the receptacle beneath the sill when not in use, and it may be readily attached to the window-sash and moved to the space left by the opening of the window when the use of the screen is necessary or desirable.

In some instances I make use of spring-catches on the screen and have them engaged with plates in the bottom of the recesses in the window-sash similar to a bifurcated arrow-head engaging with the plate or stop f⁴ f⁴, 75 forming a spring-catch, as shown in Fig. 3.

Two floating hard-rubber rollers H H are used on either side of the screen in order to make the same work evenly and to assist in 80 holding the screen in position when up; otherwise the extra weight would more than balance the sash-weights and cause the screen to fall. At the lower edges of the sills of the screen-frame I also provide two pivotal rollers H⁴ H⁴, which serve to secure more perfect 85 operation, while the rollers H H roll in recesses M M in the sides of the screen. The bifurcated arrow-head catches shown in Figs. 3 and 4 engage with stops f⁴ f⁴, which in this 90 instance may be simply pins for that purpose. The resiliency of the springy metal will cause them to lock automatically as the screen and window-sash are brought together. They may be disengaged by thumb-pieces g 95 g, by means of which they may be pressed together away from the stops.

What I believe to be new, and what I therefore wish to secure by Letters Patent, is—

1. In a window-screen and well for the same, 100 the combination of the window-sash, having perforations and slots and a catch, with a sliding screen having projections which register with the perforations in the sash and

which are adapted to be locked into position by the catches in the slots in the openings in the window-sash and the rollers at the sides of the screen, substantially as described.

5 2. A recessed screen of the character described having the rollers at the sides and provided with spring bifurcated catches, in combination with a window-sash having

catches for engagement with said spring-catches, substantially as described. 10

In testimony whereof I affix my signature in the presence of two witnesses.

THEODORE SMITH.
